UNITED STATES PATENT OFFICE.

ANGELO PERRI, OF GROVELAND, MASSACHUSETTS, ASSIGNOR TO REECE SHOE MACHINERY COMPANY, OF BOSTON, MASSACHUSETTS, A CORPORATION OF MAINE.

LASTING-MACHINE.

1,290,651.

Specification of Letters Patent.

Patented Jan. 7, 1919.

Application filed May 10, 1918. Serial No. 233,685.

To all whom it may concern:

Be it known that I, ANGELO PERRI, a citizen of the United States, residing at Groveland, in the county of Essex and State of Massachusetts, have invented certain new and useful Improvements in Lasting-Machines, of which the following is a specification, reference being had therein to the accompanying drawing.

10 This invention pertains to a novel lasting machine adapted for shoe manufacture; the function of such class of machine being to pull, stretch or shape the soft leather of the upper into place about the wooden last and 15 secure the leather in place, permanently or temporarily, preparatory to the subsequent steps in the manufacture of the shoe.

While some of the features of the present invention might be employed in a lasting machine intended to operate completely around the shoe, the specific machine herein illustrated as an embodiment of the present invention is designed more especially for lasting the sides or shanks of the shoe, after 25 the more difficult lasting operations at the ends have already been performed, for example, on machines such as shown in my prior Patents 1,168,963, of January 18, 1916, 1,222,125, 1,122,126 and 1,222,127 of April 30, 1917, and 1,260,034, of March 19, 1918. The toe and heel mechanisms in said prior 35 patents take care of both ends or tips of the shoe, and, although the shanks or sides might be lasted by hand while the shoe still remains in my prior machines, as stated 40 therein, I prefer to supplement said machines by the machine of the present application, to which the shoe is to be removed for the so-called side lasting operation. The 45 art presents several examples of machines capable of lasting the sides of shoes, of which I mention expired patent of Ladd No. 597,321, of January 11, 1898; but prior machines have never proved entirely satisfactory, and the main object of the present invention is to afford a lasting machine of superior efficiency, convenience, simplicity and speed, worthy of superseding mere hand implements.

50 The further objects and the advantages of the present invention, the elements or instruments involved, and their preferred mode of action, can be more readily explained during or after the following description, which in connection with the ac-

companying drawings illustrates a convenient embodiment of the principles of the present invention. To the attainment of the several objects and advantages referred to, the present invention consists in the novel 60 lasting machine, and the novel features of combination, construction, arrangement, action and detail herein shown or described.

In the accompanying drawings, Figure 1 is a left side elevation of the upper part or 65 head of a lasting machine illustrating the present invention, it being understood that the same may be located at the top of the usual post or standard, at the foot of which may be located pedals for controlling the 70 driving and stopping mechanism and effecting other control. Fig. 1 shows the parts in the stage of action at which the pincers have taken hold of a part of the edge of the leather upper, and are about to pull or 75 stretch it into place around the bottom of the inverted last. Fig. 1^a shows a structural detail. Fig. 2 is a view similar to Fig. 1, less complete in detail and showing the parts in that later stage of operation 80 when the driver is about to drive a tack through the portion of the upper which has just been stretched and laid in place beneath the last. Fig. 3 is a front elevation showing the parts in the same position as 85 in Fig. 1.

Figs. 4, 5 and 6 illustrate the details of the wiping and tack-carrying member, Fig. 4 being a top view, Fig. 5 a left elevation, and Fig. 6 a front elevation.

Fig. 7 is a section on the plane 7—7 of 90 Fig. 1, showing partly in top plan certain details of the connections.

Figs. 8 and 9 illustrate the details of the tack separating mechanism, Fig. 8 being a 95 top plan view, and Fig. 9 a front elevation, that is, looking toward the side of Fig. 8 nearest the observer.

The shoe is indicated in the drawings in its inverted position, which is the usual 100 position for side lasting. The wooden last X is surrounded by the upper x of the shoe, and the insole x', which may have a lip x² for the subsequent attachment of a welt.

In general the machine comprises pincers 105 capable of grasping and pulling the extending edges of the upper, a wiping and tack positioning member, which smooths the leather into place and carries the tack into position, a tack feeding mechanism for sup- 110

plying tacks thereto one at a time, and a driver adapted to drive the successive tacks through the edge of the upper into the last; and the machine being power operated, 5 there is a drive shaft which actuates cams or cranks, through which the different instruments are operated in a predetermined order or harmony, through cycle after cycle, until the power is disconnected by throwing 10 off a clutch or the like. For feeding the shoe through the machine as the upper is progressively pulled and the tacks driven, the judgment of the operator may be relied on, he holding the shoe in hand and advancing 15 it with the aid of a fixed guide in the machine. With this general outline the details of the machine may be described as follows:

The head casting 12 constitutes the framework of the movable parts to be described, 20 and it has an overhead extension 13. Other fixed and frame parts will be described in connection with the various mechanisms.

As the operations on a shoe proceed, the 25 shoe is moved forwardly, for example, by hand, assisted by guide means consisting preferably of a rest or guide 14, against which the side of the last or upper bears, and a second shoe rest or guide 15, the shoe 30 insole being held up against this during operations.

Journaled in bearing 17, 17, provided in the head casting, is the power shaft 18, extending forwardly and rearwardly, with a 35 belt pulley 19 at its rear end.

From the power shaft are derived the several motions of the active instruments of the machine, the pincers, the wiper member, the tack driver and the tack feed. While 40 these operations might be performed through shaft cranks and suitable connections, I prefer and herein illustrate a number of rotary cams, 21, 22, 23, and 24, mounted directly on the shaft 18.

45 The pincers consist of the opposing jaws 41 and 42, which in this machine have three kinds of movements, first, closing and opening movements, second, a lifting or pulling movement, and the opposite or return, and, 50 third, a bodily movement with its carrier into and away from operative position, it being necessary for the pincers to be out of the way at the time of the tack driving action.

55 I will first describe the train of connections from the power shaft for closing and opening the pincers, which are shown closed in Fig. 1 and open in Fig. 2. The cam 23 on the power shaft bears downwardly upon 60 the stud 26 of a spring-lifted cam lever 27, which has an up and down movement. This lever 27 transmits the downward thrust of the cam to a lever 28, pulled upwardly by a spring 29. The rear end of the lever 28 65 is curved downwardly and slotted at 30 to

engage a follower or stud 31, provided on a slide 32. This slide is movable forwardly and rearwardly in suitable guideways, which will be explained later, and near its forward end has swiveled to it a block 33, 70 through which slides the rear end of a rod 34, having adjusting nuts 35 at its rear end, and surrounded by a spring 36 pressing the rod forward. The front end of the rod 34 is connected to the upward arm of a small 75 bell crank lever 37, which is pivoted at 38, while the rearwardly extending arm is provided with a stud 39, co-acting with the curved or cam-shaped upward extension 40 of the rear pincer jaw 41. When the cam 23 80 throws down the levers 27 and 28, this throws upwardly the stud 39, which forces the rear pincer jaw forwardly against the front pincer jaw 42, resisted by a spring 43, which subsequently opens the pincers. 85

The pulling or stretching motion of the pincers in this machine is an upward swinging motion about an axis approximately at the level and forward of the jaws, and for this purpose the forward pincer jaw 42 is 90 formed with or connected to a swinging carrier 54, suitably pivoted at 55, and actuated from the power shaft as follows. The cam 21 acts on a centrally pivoted follower lever 46, swinging fore and aft, its lower end being connected to a block 47, through which slidably extends rod 48, which has adjusting nuts 49 at its rear extremity, and a compressed spring 50, surrounding the rod between the block and the rod's forward end, 95 which is pivoted through a stud 51 to a fore and aft moving slide 52, directly above the slide 32, previously referred to. Extending forwardly again from the same pivot stud 51 is a second rod 53 connecting the slide 52 100 with the upper end of the carrier arm 54, already mentioned, which is pivoted at its lower end at 55, and has the front pincer jaw 42 formed integrally with it. From this description it will be seen that the action 105 of the cam 21 is to swing the pincer carrier arm 54 so as to put the pincers through their pulling and return movements.

In order that the opening and closing movements may be independent of the pulling movements of the pincers, the following construction is employed. In describing the pincer closing connections, it was not explained how lever 28 was supported. It will now appear that this lever is fulcrumed to 110 the slide 52, preferably by the same stud or pivot 51, which also engages with the rods 48 and 53. The two slides 32 and 52 are for convenience in mutual engagement, as already explained, and the two are guided 115 in their fore and aft movements by suitable guideways 57 above the upper slide 52, and 58 below the lower slide 32. The result of this construction is that, when the cam 21 acts to move the pincers bodily, the lever 28 120 125 130

of the jaw closing connections is carried bodily, and with it all of the jaw closing connections. It will be noted that the cam lever 27 is shaped to permit a relative fore and aft motion with relation to the roller stud of the lever 28 beneath it.

In order to bodily shift the pincer mechanism into and from position, the pincer carrier arm 54 is pivoted at 55 on a shifting lever 61, which in Figs. 1 and 2 is partly concealed behind the other parts, and is fulcrumed at 62, where it has extending downwardly from the fulcrum point a short arm 63. In order to swing this arm 63, and thereby the entire pincer mechanism between the operative position, Fig. 1, and the forward or retracted position, Fig. 2, the following connections from the cam 22 of the power shaft may be employed. The cam 22 is engaged by follower arm 66, fulcrumed at 67, and having two downward extensions, the short one, 68, of which is connected by a forwardly extending crooked link 69 directly to the short downward arm 63 of the lever 61 before mentioned. By these connections the cam 22 is capable of swinging the pincers between operative and inoperative position.

I will now describe the instrument which preferably serves both for positioning the successive tacks to be driven and for wiping or pressing the stretched work snugly over the bottom of the last in the act of moving inward to position the tack. This positioning and wiping member takes the form of a slide 71, seen in its retracted and advanced positions in Figs. 1 and 2, respectively, and shown separately in Figs. 4, 5 and 6. The wiper itself is shown as a thin, curved member 72, secured at the bottom of the slide 71, and centrally recessed at the point where the tack is to be driven between the two sides of the wiper. A device for holding each tack is shown as comprising a pair of opposed fingers 73, 73, mutually pivoted at 74 on the slide 71, and having their right or forward ends specially formed, each with a recess 75 of half-conical shape, so that the two fingers when closed together present a conical recess adapted to receive and hold a tack, point downward, ready to be driven into the work, and yet held against the possibility of injuring the work until driven. The two fingers 73 are additionally recessed near the pivot to coöperate with a central stop member 76, against which the two normally contact; and a pair of opposite side springs 77 bear with suitable pressure against the two fingers to hold them normally in this position, yet permitting yielding as the tack is driven and as the slide is withdrawn from the shoe.

As shown in Fig. 1, the tack positioning and wiping member or slide 71 is mounted in a slideway 79 on the frame or head 12.

After the pincers have pulled each portion of the leather, it is the function of the slide 71 to move forwardly, causing the wiping and laying down of the leather over the last, and holding the tack in position until driven by the driver, as will be explained, whereupon the slide retracts. Connections from the power shaft 18 for so actuating the slide may be as follows. The cam 22, as already explained, acts upon a follower arm 66, fulcrumed at 67. This arm has a downwardly extending arm 80, which at its lower end is vertically slotted at 81 and engaged by the rear end of a stud 82, connected by a link 83 with a stud 85 on the slide 71. Turn buckle 84 adjusts the length of the link. The adjustable slot and stud 81, 82, and the adjustable link 83 permit variation of the extent of throw and range of movement of the slide 71, carrying the tack fingers and wiper.

The tack driver is shown as a cylindrical pin 86, suitably held in the lower end of a cylindrical rod 87, movable up and down through upper and lower bearings 88, 90 formed in a hollow frame or yoke 89. This yoke is rendered swingable, so that the driver may be positioned over the tack or swung to the right out of position during the pulling and wiping actions. For this purpose the yoke 89 is provided with trunnion bearings 90 at its front and rear sides, formed on a fixed bracket 91 projecting forwardly from the frame for this purpose.

The yoke 89 and driver 87 may be swung by the following connections from the power shaft 18. See Figs. 1, 2 and 7. The cam 22 actuates the follower arm 66, as already explained. The upper end of this oscillating arm is shown connected by a link 93 (adjustable to regulate the throw) to the leftward projecting arm 94 of a bell crank lever, whose forwardly projecting arm 95 is connected by a link 96 to a boss 97, formed on the lower bearing 88 of the swinging yoke. By this arrangement, when the cam 22 throws its follower rearward, the boss 97 is moved to the left, thus shifting the driver leftward into operative position over the tack.

For causing the driver up and down movements, I prefer a spring acting in one direction, and cam connections in the opposite direction. Preferably the connections act to lift the driver and release it, and the spring thereupon throws it down with accelerated force and momentum upon the tack. The upper end of the driver rod 87 is shown as having a key connection 99 with the upper bearing 88, so as to prevent the driver from twisting. Above the upper bearing the driver is provided with a head, including a number of leather washers 100, to take the brunt of the impact. Thereabove a connecting pin 101 extends between the top of the

driver rod and the extremity of a spring-pressed arm 102. This arm is mounted on a hub surrounding a stud 103, secured in an upwardly extending frame bracket 104. A stout coil spring 105 surrounds the stud 103, and is put under considerable tension, so that a powerful pressure is constantly bearing down on the driver rod.

In order to lift the driver rod and at the proper instant suddenly release it to descend and impact upon each tack, the cam 24 is provided on the power shaft, as shown in Figs. 1 and 2, and in front view in Fig. 3. Looking at Fig. 3, the cam 24, which turns counter clockwise, is constructed with a concentric surface followed by a recess, giving a sudden drop. Coöperating with the cam is a stud 107, secured by a collar 108 to the driver rod at approximately the height of the trunnion bearing 90 of the driver yoke frame, so that this stud does not change its position when the driver mechanism swings. Fig. 3 shows that the axis of the cam 24 is somewhat to the left of its follower stud 107, and this in connection with the illustrated contour of cam, I find to give an exceedingly quick releasing and dropping action of the driver, which immediately after the blow is again raised by the cam to its normal, inoperative position. By this arrangement the driver is caused to drop upon a tack once in each shaft revolution or cycle.

In this machine a single tack is dropped between the tack holding fingers 73 into the conical recess 75 in each cycle of actions, that is, when the slide 71 has withdrawn rearwardly from the work, so that on its next forward stroke it will carry a tack to the position where it will be driven in the next descent of the driver.

The tack supply is maintained in a reservoir 111, and fed therefrom in a series down a slotted chute 112. The structure of the reservoir and chute may be in accordance with well known devices already used for this purpose. At the foot of the chute is a fixed block 113, having a vertical hole 114, through which tacks may drop into the conical recess between the tack holding and positioning fingers 73. See Figs. 1, 3, 8 and 9.

Within the lower end of the chute 112 is a picker blade 115, and below this a movable tack retainer or supporting plate 116. The picker blade is so arranged that, when moved forwardly or into the chute, it separates the second tack from the foremost one and confines or holds it back, and the retainer is so arranged that, when moved away from the chute, it releases the foremost tack to drop through the hole 114 to the tack positioning member beneath. The tack retainer may be supported by a spring 117, bent, as shown in Fig. 8, to assist in its actuation. These parts may be operated by a slide 118, which directly carries the confiner or picker blade and

has a shoulder 119, adapted to strike the spring 117 and thus withdraw the retainer 116, after the picker has separated the first and second tacks. For automatically moving the slide 118 to give these results in harmony with the other operations in the machine, a lever is shown having a slotted arm 120, connected to the slide 118, and a rearwardly extending arm 121 having a cam surface 122, the lever being pivoted at 123. Co-operating with the cam 122 is a roller stud 124, which is mounted at the underside of the block 33, already mentioned in describing the pincer closing connections. This block reciprocates forwardly and backwardly, and, as will be clear on Fig. 8, when the block and stud 124 move forwardly, this will permit the lever 120—121 to swing, under the influence of a pusher 125 impelled by a spring 126, thereby thrusting the slide 118 forwardly, separating the foremost tack, and subsequently releasing the tack to drop into the tack positioning member, while the latter stands in its retracted position. The described tack feeding devices have been made the subject of divisional application, Serial No. 256122, filed September 28, 1918.

The entire operation of the machine will be understood from the above description and from the illustrated timing of the several cams. Preferably the operation will be as follows. Starting with the Fig. 1 position, in which the pincers are shown closed upon the edge of the leather or upper, the closed pincers first swing upwardly with a pulling movement, stretching the leather at the point engaged. Overstrain and injury are prevented by the yielding of the spring 50, which is set to yield if a given limit of tension is exceeded. The tack positioning and wiping member 71, having received a tack, has started forwardly and now engages and presses the leather forward and down against the sole of the shoe. While this is occurring the pincers open to release the leather, and the entire pincer mechanism swings bodily forwardly out of the way of the wiper and driver. The driver, which in the meanwhile has stood off to the righthand side, is now swung leftward directly in over the member 71. Fig. 2 shows this stage of operation. Now, the tack positioning member having come to rest with the tack held in proper position between a sixteenth and an eighth of an inch from the shoe edge, the driver is about to descend, being released by the turning of the cam 24 to the point where its shoulder ceases to support the driver against the depressing force of the overhead spring 105. These operative actions are followed by the reverse actions, the driver lifts and swings off to the right, the operator moves the shoe along a suitable distance to a fresh point, the pincers shift bodily rearwardly, and

then down, and then close upon the leather, the pressure being limited by the yield of spring 36, while at the same time the tack positioning and wiping member moves to 5 the rear to where it may receive a new tack, released by the tack feeding mechanism. This brings the parts again to the Fig. 1 position, completing a cycle of operations, which is repeated cycle after cycle as long

10 as the operator holds a shoe in position and maintains closed the clutch of the machine.

It will thus be seen that I have described a lasting machine embodying the principles and obtaining the advantages of the present 15 invention, and other advantages will be apparent to those skilled in the art. Since many matters of combination, arrangement, design and detail may be variously modified without departing from the underlying 20 principles, I do not intend to limit the invention to such features except so far as set forth in the appended claims.

What is claimed is:

1. A lasting machine including in combination, a tack positioning instrument, a pulling mechanism comprising a pincers having pulling movements, a driver having driving and retracting movements, means for bodily shifting the pincers longitudinally to and 25 from the work, and means for shifting the driver laterally to and from its tack driving position relatively to the tack positioning instrument.

2. A lasting machine including in combination, a tack positioning instrument, a pulling mechanism comprising a pincers having pulling movements, a driver having driving and retracting movements, means for bodily shifting the pincers forwardly after pulling 30 and releasing the work, means for advancing the tack positioning instrument, and after the driving shifting it rearwardly 40 from position, and means for shifting the driver laterally to and from its tack driving position relatively to the tack positioning instrument.

3. A lasting machine including in combination, a tack positioning mechanism, a pulling mechanism comprising a pincers having 50 pulling movements, a driver having driving and lifting movements, and means for shifting the driver laterally to and from its tack driving position, comprising a frame in which the driver slides, and automatic connections to oscillate the frame about a fore 55 and aft axis relatively to the tack positioning instrument.

4. A lasting machine including in combination, a tack positioning mechanism, a pulling mechanism comprising a pincers having 60 pulling movements, a driver having driving and lifting movements, and means for shifting the driver laterally to and from its tack driving position, comprising a frame in 65 which the driver slides, and automatic con-

nections to oscillate the frame about a fore and aft axis, said connections including an adjustment for altering the throw.

5. A lasting machine including in combination, a tack positioning mechanism, a pulling mechanism comprising a pincers having pulling movements, means for bodily shifting the pincers longitudinally to and from the work, a driver having driving and lifting movements, and means for shifting the 70 driver laterally to and from its tack driving position, comprising a laterally swinging hollow yoke frame in which the driver slides, and a device interior of the hollow frame 75 engaging the driver substantially at the frame axis of swinging for causing driving movements thereof.

6. A lasting machine including in combination, tack positioning and driving means, and a pulling mechanism comprising a pincers having closing and opening movements, a pincers carrier swingable upwardly about a pivot substantially at the pincer level 85 for the pulling movements, and a shifting support for such carrier pivot by which the pulling mechanism may be bodily shifted 90 from and to operative position.

7. A lasting machine including in combination, tack positioning and driving means, and a pulling mechanism comprising a pincers having closing and opening movements, a pincers carrier swingable about a pivot substantially at the level and forward 95 of the pincer jaws for bringing about the pulling movements, and means by which the pulling mechanism may be bodily shifted 100 from and to operative position.

8. A lasting machine including in combination, tack positioning and driving means, and a pulling mechanism comprising a pincers having closing and opening movements, a pincers carrier swingable about a pivot approximately at the level of the pincers 105 for the pulling movements, and a shifting support for such carrier and pivot by which the pulling mechanism may be bodily shifted 110 from and to operative position, said carrier and support being pivoted together near their lower ends, said support being fulcrumed near its upper end and said carrier having an upward extension and means for actuating said extension to give pulling movements to the carrier.

9. A lasting machine including in combination, tack positioning and driving means, and a pulling mechanism comprising a pincers having closing and opening movements, a pincers carrier swingable for the pulling movements, and a shifting support 115 for such carrier by which the pulling mechanism may be bodily shifted from and to operative position, said carrier and support being pivoted together near their lower ends, said support being fulcrumed near its upper end, and said carrier being actuatable 120

by a connection to its upper end near the fulcrum of said support.

10. A lasting machine including in combination, tack positioning and driving means, and a pulling mechanism comprising a pincers having closing and opening movements, a pincers carrier swingable for the pulling movements, a pincer closing member mounted on the carrier, consisting of a bell crank lever, a cam between said lever and pincer, automatic connections for swinging the bell crank lever to close the pincers, and automatic connections for swinging the carrier to give pulling movements to the pincers.
15. 11. A lasting machine including in combination, a work pulling pincers, a tack positioner, a tack driver, a power shaft, and connections from said shaft to said instruments comprising a pair of parallel slides, a cam for oscillating the first slide, connections from the first slide for giving pulling and return movements to the pincers, a cam for oscillating the second slide, the connections for oscillating the second slide being mounted on the first slide whereby the second slide partakes of the oscillation of the first slide, and connections from the second slide for closing and opening the pincers.
20. 12. A lasting machine including in combination, a tack positioner, a tack driver, a work pulling pincers comprising two jaws, a pincers carrier having one jaw rigid with

it and the other pivoted thereto, a cam extension of the pivoted jaw, a cam stud movably mounted on the carrier, and means for operating the cam stud and the carrier to close the jaws and pull.

13. A lasting machine including in combination, a work pulling pincers, a tack driver, and a tack positioner comprising a retractable finger carrier, and a pair of rigid pivoted fingers thereon, a single pivot stud for both said fingers, a single interior stop pin in front of said stud, both said fingers interiorly recessed so as to contact said stop pin when the fingers are in normal contacting position, and separate resilient means unattached to said fingers but pressing oppositely upon the same to hold them to said stop pin.

14. A lasting machine including in combination, a work pulling pincers, a tack driver, a tack feeding chute, a perforated block at the chute terminus, a tack positioner comprising a retractable finger carrier, connections for reciprocating said finger carrier between a point beneath said perforated block and tack driving position, and means for adjusting said connections to adjust the retracted carrier position and its throw.

In testimony whereof, I have affixed my signature hereto.

ANGELO PERRI.
